UNITED STATES PATENT OFFICE

STOP FEED PLUG FOR TEXTILE KNITTING MACHINES

Charles Strzalkowski, Milwaukee, Wis.

Application February 10, 1936, Serial No. 63,195
Renewed May 27, 1937

10 Claims. (Cl. 66—126)

This invention appertains to knitting machines, and more particularly to a novel appliance for use in conjunction with full-fashioned stocking knitting machines.

As is well known, the standard knitting machine generally includes (for the "Legger") eighteen stocking knitting sections, and each section embodies seven or more thread carriers. Considerable waste takes place when a thread breaks, as it is desirable to continue the knitting operation, and all of the legs or feet (as the case may be) on the machine are made before attempting to remedy the break, and thus the knitting operation and the feed of the thread continues on the section having the broken thread. Consequently, the stocking knitted by the section with the broken thread is ruined and must be discarded as waste. Also, the broken thread is liable to become entangled, necessitating the re-threading of the section, which is a lengthy and tedious operation.

It is, therefore, one of the primary objects of my invention to provide novel means for stopping the feed of the thread at the thread carriers of one section of the knitting machine when a thread breaks in said section to effectively prevent the waste of thread and the necessity of re-threading the section.

Another salient object of my invention is the provision of means associated with the thread carriers for engaging the thread in the thread guide tubes of the carriers and without injury to said tubes, so as to firmly hold the threads against movement and displacement.

Another object of my invention is to provide a member entirely independent of the knitting machine adapted to be manually placed on and removed from the machine for frictionally engaging the thread and the thread-carrier, whereby no obstructions or projecting portions will be formed on the thread-carrier, the member being formed from cushioning material so that injury to the thread and the thread-carrier will be prevented.

A further object of my invention is the provision of removable members adapted to be wedged into the guide tubes of the carriers for firmly holding the thread in said tubes and against movement, whereby to effectively stop the feed of thread for any reason during the operation of the machine.

A further important object of my invention is the provision of resilient plugs shaped to snugly fit in the guide tubes for engaging a thread therein, the resilient plugs preventing injury to the thread and to the highly polished inner surface of the guide.

A still further object of my invention is to provide an improved appliance for use in conjunction with full-fashioned stocking knitting machines,

which will be durable and efficient in use, one that will be simple and easy to manufacture, and one which can be placed upon the market at an extremely low cost.

With these and other objects in view, the invention consists in the novel construction, arrangement, and formation of parts, as will be hereinafter more specifically described, claimed, and illustrated in the accompanying drawing, in which drawing:

Figure 1 is a fragmentary perspective view of a part of one section of a full-fashioned stocking knitting machine.

Figure 2 is a fragmentary, detail, side elevation illustrating the normal position of a thread on the thread carrier and in the guide tube.

Figure 3 is a fragmentary side elevation of a thread carrier, with the guide tube in section, showing one of my improved devices in position for firmly holding the thread against feeding movement and detachment from the tube.

Figure 4 is an enlarged, detail, front elevation of one of the improved plugs.

Figure 4A is a view similar to Figure 4, showing a slightly modified form thereof.

Figure 5 is a side elevation of a further form of a plug which can be utilized.

Referring to the drawing in detail, wherein similar reference characters designate corresponding parts throughout the several views, the letter M generally indicates a fragment of a section of a full-fashioned stocking knitting machine. This machine M is of the usual or any desired standard construction, and only a sufficient portion of the machine has been shown to illustrate the use of my improved appliance.

As illustrated, the machine embodies the bed and frame 2, in front of which traverses a plurality of thread carriers 5. These carriers 5 lay the thread upon the sinkers 3 and dividers 4 along the needles 6. The knock-over bits 7 are shown in Figure 1 below the dividers and sinkers. Each thread carrier 5 includes a guide tube 8 for the threads 9.

The inner surface or bore of the guide tube 8 is highly polished so as to prevent injury to the thread and to facilitate easy travel of the thread through the tube.

As set forth above, when a thread breaks in one section of the stocking knitting machine, the machine is allowed to run until all of the stockings are knitted on the machine, which results in the feeding of the thread to the section in which the broken thread occurs, resulting in great waste of material.

In accordance with my invention, I provide novel means for stopping the feeding of the thread at the thread carriers 5, so that the thread to any particular section can be stopped without stopping the entire knitting machine.

In the present instance, I employ an elongated

solid plug 10, which is so shaped as to be snugly received within a guide tube 8 against the thread 9, so as to wedge the thread therein against further movement. As shown in Figure 4, the lower 5 end of the plug 10 can be slightly tapered so as to facilitate the insertion of the plug or pin within the guide tube 8, and the upper end of the plug can be provided with a head 11 to limit the insertion of the plug in a tube and to facilitate the 10 withdrawing of the plug from a tube after the plug has served its purpose.

As shown in Figure 4A, the head 11' and a part of the shank can be flattened, as at 12, and this flattened part 12 can be placed adjacent to the 15 thread to be held.

If preferred, and for the sake of ease of manufacture, the plug can be uniformly tapered from its upper end to its lower end, as indicated by the reference character 13. This plug is illustrated in Figure 5 of the drawing. The upper end of the tapered plug, shown in Figure 5, is of a greater diameter than the interior diameter of the tube, and consequently the plug gradually wedges itself in place in the tube when the plug is inserted in said tube.

In order to prevent injury to the thread and to the highly polished inner surface of the tube 8, the plugs are preferably made from resilient live rubber. Obviously, when the plugs are 30 formed from resilient rubber, the same will give when forced into a guide tube and thus will not scratch the tube or hurt the thread.

The construction of the plugs is such that the same can be cheaply made, and the same can be 35 readily and easily inserted in the guide tubes or removed therefrom when the occasion demands.

Obviously, the invention is open to certain modifications and changes, and the invention primarily resides in a member formed from elastic 40 cushioning material, such as rubber, which is entirely independent of the thread-carrier and manually movable into and out of its operative engagement on the carrier, whereby no change is necessary in the carrier itself, and so that no 45 obstructions or projecting portions will be formed on the carrier. Particular stress is laid on the fact that the member is of elastic cushioning material, in that the member will frictionally engage the carrier and thread for firmly holding 50 the thread against movement on the carrier. This is important, as where a fine silk thread is held by metallic means rupture of the thread strands is liable to occur.

From the foregoing description, it can be seen 55 that I have provided an exceptionally simple and effective means for saving thread when a thread breaks in a section of a stocking knitting machine.

Changes in details may be made without departing from the spirit or the scope of my invention, but what I claim as new is:

1. In a full-fashioned hose knitting machine, the combination with a thread carrier having a guide tube through which the thread travels, of a removable plug manually insertible in said tube 65 against said thread for holding the thread against movement in said tube during normal operation of the machine.

2. In a full-fashioned hose knitting machine, the combination with a thread carrier having a 70 guide tube through which the thread travels, said guide tube having its inner surface highly polished, of a plug removably fitted in said tube

against the thread to hold said thread against movement during normal operation of the machine, the plug being formed from cushioning material, whereby injury to the thread and the highly polished inner surface of the guide tube is prevented. 5

3. In a full-fashioned stocking knitting machine, the combination with a thread carrier having a guide tube at its lower end through which the thread travels, of a device for wedging the 10 thread in the guide tube against movement during the normal operation of the machine, including an elongated cylindrical body tapering toward its lower end, said body having one face thereof flattened. 15

4. In a full-fashioned stocking knitting machine, the combination with a thread carrier having a guide tube at its lower end through which the thread travels, of a device for wedging the 20 thread in the guide tube against movement during the normal operation of the machine, including an elongated cylindrical body tapering toward its lower end, said body being formed from resilient rubber.

5. A device for stopping the feeding of thread 25 through the guide tube of a thread carrier of a full-fashioned stocking knitting machine, comprising an elongated body manually insertible in the tube having its upper end of a greater diameter than the interior diameter of the tube 30 with which it is to be associated.

6. A device for stopping the feeding of thread through a thread carrier of a full-fashioned stocking knitting machine, comprising an elongated body having its upper end of a greater 35 diameter than the interior diameter of the tube with which it is to be associated, said body being formed from cushioning material.

7. A device for stopping the feeding of thread through a thread carrier of a full-fashioned 40 stocking knitting machine, comprising an elongated body having its upper end of a greater diameter than the interior diameter of the tube with which it is to be associated, said body being formed from resilient rubber. 45

8. A device for stopping the feeding of thread through the thread carrier of a full-fashioned stocking knitting machine, comprising an elongated cylindrical body gradually tapering from its upper end toward its lower end, said body being formed from resilient rubber and having its upper end of a greater diameter than the tube of the thread carrier with which it is to be associated. 50

9. In a full-fashioned hose knitting machine, the combination with a thread-carrier having a 55 guide through which the thread travels, of an elastic member formed from cushioning material manually movable into and out of frictional gripping contact with the carrier and thread for holding the thread against movement during normal operation of the machine, and when said member is in its frictional contact with the carrier and thread.

10. A device for stopping the feeding of thread through the guide tube of a thread-carrier of a 65 full-fashioned stocking knitting machine comprising, a member formed from elastic cushioning material adapted to frictionally engage the carrier and thread to stop the feeding of the thread through the carrier. 70
